(57) **CLAIM**

I claim the ornamental design for a flange wrench, as shown and described.

DESCRIPTION

FIG. 1 is a perspective view of the flange wrench. FIG. 2 is a front view of the flange wrench of FIG. 1; FIG. 3 is a back view of the flange wrench of FIG. 1; FIG. 4 is a left side view of the flange wrench of FIG. 1; FIG. 5 is a right side view of the flange wrench of FIG. 1; FIG. 6 is a top view of the flange wrench of FIG. 1; and, FIG. 7 is a bottom view of the flange wrench of FIG. 1. Broken lines illustrate text and other images and form no part of the claimed design.

The flange wrench is shown with a symbolic break in its length. The appearance of any portion of the article between the break lines forms no part of the claimed design.
